COMBINED ELECTRIC PROTECTION AND
WARP STOP FOR LOOMS

Raymond F. Dion, Leominster, Mass., assignor to
Crompton & Knowles Loom Works, Worcester,
Mass., a corporation of Massachusetts

Application April 3, 1950, Serial No. 153,687

9 Claims. (Cl. 139—341)

1

This invention relates to looms utilizing electric protection and electric warp stop motions and it is the general object of the invention to interconnect the circuits for the protection and the warp stop motion in such manner that a single solenoid can be controlled to effect stopping of the loom when a shuttle is running slow or a drop wire falls.

A type of electric protection which has been proposed heretofore utilizes a continuously energized electro-magnetic device under control of two parallel circuits, one or the other of which is always closed so long as the shuttle is running on time. In this type of electric protection the timer switch opens at a time in the cycle of the loom when the shuttle is running on time reaches a given point along the length of the lay between the shuttle boxes, and a second switch located at said point is closed by the shuttle so that current is temporarily shunted from the timer switch through the shuttle operated switch to maintain the electro-magnetic device in a state of constant energization. If, however, the shuttle should be late it fails to close its switch when the timer switch is open and the solenoid or relay becomes deenergized to effect prompt loom stoppage.

Electric warp stop motions ordinarily operate with a solenoid which is deenergized and upon falling of a drop wire a circuit is completed through the solenoid to lift a link or its equivalent into the path of a knock-off lever. The electric protection therefore requires a continuously energized solenoid or relay as a condition of continued loom operation, whereas the usual electric warp stop motion employs a normally open circuit. It is an important object of the present invention to reconcile these conflicting requirements by providing interconnected protection and warp stop electric circuits in which closure of the warp stop circuit prevents closure of the protection circuit.

It is a further object of the invention to provide a normally closed protection circuit effective when opened to cause loom stoppage, and place in the circuit a normally closed switch which during closure of the protection circuit will be opened by closure of the warp stop circuit.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a side elevation of part of a loom having the invention applied thereto, and

Fig. 2 is a diagram showing the electric circuits utilized with the invention.

Referring more particularly to Fig. 1, the loom frame 1 supports top and bottom shafts 2 and 3 the former of which turns once for each beat of the loom while the latter shaft turns once every other beat of the loom. The loom has a lay 4 driven from the top shaft 2 by connectors one of which is shown at 5. The usual warp thread system W is controlled by harness mechanisms indicated generally at 6 which divides the threads into top and bottom warp sheds W1 and W2, respectively.

The top shaft will ordinarily turn in the direction of arrow a, Fig. 1, to cause the lay to reciprocate backwardly and forwardly, and when the lay is on its backward stroke the shuttle S will generally be picked and be in flight across the loom throughout the remainder of the backward stroke of the lay and for a part of the ensuing forward stroke.

The loom has shipper mechanism designated generally at 10 controlling loom operation by mechanism not shown herein but well understood. A shipper or brake handle 11 is connected to a rod 12 extending rearwardly and pivoted to the upper end of a lever 13 pivoted as at 14 to a knock-off mechanism designated generally at 15. A solenoid 16 is held in fixed position on the mechanism 15 and has a core 17 connected to a knock-off link 18. A regularly rocking knock-off lever 19 is supported on a pivot 20 carried by the mechanism 15 and is caused to rock on a working stroke in a counter-clockwise direction as viewed in Fig. 1 once for each pick of the loom. This rocking is effected by a cam 21 having oppositely extending riser points 22 for engagement with an arm 23 of lever 19. The parts are so proportioned that if link 18 should be down in the path of lever 19 as the latter has a working stroke force will be transmitted through the rod 12 to the loom controlling or shipper mechanism 10 to move the latter to loom stopping position, whereupon the loom brake will promptly stop the loom. A stop 24 holds link 18 in the path of lever 19 when solenoid 16 is deenergized. The knock-off mechanism may be similar to that shown in Payne Patent No. 1,873,465.

The warp threads may be provided with drop wires 25 strung along contact bars one of which is shown at 26 in Fig. 2. These bars will ordinarily have a grounded outer electrode 27 and an inner insulated electrode 28. Whenever a drop wire falls due to breakage or undue slackness of a warp thread the electrodes 27 and 28 are electrically

connected. The warp stop motion may be similar to that shown in Payne Patent No. 1,852,217.

The matter thus far described except as noted hereinarter is of usual construction and operates in the usual manner. The shuttle will ordinarily pass out of the warp shed during forward motion of the lay early enough to prevent breakage of warp threads, but should the shuttle be slow in its flight across the loom provision must be made for effecting prompt loom stoppage to prevent a warp smash.

The electric protection includes a timer switch TS which opens at regularly recurring intervals once every pick or beat of the loom, and also a shuttle operated switch SS. The timer switch includes a blade 30, see Fig. 2, which is periodically moved by a cam 31 secured to and turning with the top crank shaft 2, see Fig. 1. The blade 30 may actually be operated by a switch arm 32 having direct contact with the cam 31 so that whenever the latter pushes the arm rearwardly, or to the right in Fig. 1, the switch will open. Blade 30 will normally engage contact 33 to close switch TS except when moved by tappet 34 of the cam.

The shuttle switch SS has a blade 35 which is normally in open position but is closed by depression of a plunger 36 extending vertically through and slidable in the lay 4 by the shuttle as the latter passes over the plunger. If desired, a time delay mechanism may be associated with the switch SS to hold it closed for a given part of the loom cycle after the plunger 36 is depressed by the shuttle 30. This time delay or holding mechanism may include a hook lever 37 pivoted at 38 on the lay for cooperation with a holding arm 39 associated with the switch SS. A stationary stop 40 is positioned for engagement with the lower end of lever 37, when the lay approaches front center, and lever 37 normally tends to turn in a clockwise direction as viewed in Fig. 1.

In the operation of the electric protection the switch TS will be normally closed so that, referring to Fig. 2, current can flow in the following normally closed protection circuit: transformer T, wire 45, normally closed switch 46 to be described hereinafter, wire 47, solenoid 16, wires 48, 49 and 50, contact 33, blade 30, and wires 51 and 52 back to the transformer. Current flowing in this circuit will keep the solenoid energized as long as switch TS is closed and link 18 will be held normally above the path of movement of lever 19. Wires 50 and 51, and switch TS, may be considered a normally closed branch of the protection circuit.

The time for the opening of timer switch TS by the cam 31 is determined by the time at which shuttle S will normally be able to depress the plunger 36 when it is in proper flight across the lay. If, for instance, this time is while the lay is at or near back center the timer switch will be set to open at this time to break the aforesaid circuit, but depression of plunger 36 by the shuttle at the proper time will complete another branch of the protection circuit as follows: wire 55, contact 56 of switch SS, switch blade 35, and wire 57 connected to wire 52. This second branch may be considered as normally open. The two branches are in parallel and if the shuttle is running properly one or the other of the branches will always be closed so that the solenoid 16 will be normally continuously energized and the knock-off lever will not be able to stop the loom. Should the shuttle be run-

ning slow, however, switch SS will close late in the loom cycle after the switch TS is open, in which event both branches will be open and the solenoid 16 will become deenergized to release link 18 and the latter will fall into the path of lever 19 so that the latter will stop the loom as already described. The branches of the protection circuit and switch SS may be similar to part of the electric protection set forth in copending application Serial No. 134,001 filed December 20, 1949, by Moss.

The warp stop motion circuit is normally open, but when a drop wire falls to connect the electrodes 27 and 28 current will flow in the following warp stop circuit: transformer T, wires 45 and 60, the contact bar 26, electro-magnet 61, wire 62, a shipper handle controlled switch 63, and wire 64. From the latter wire the circuit will be completed through one or the other of the branch circuits back to the transformer to cause energization of the electro-magnet 61 and opening of the switch 46, thereby opening the protection circuit and permitting link 18 to fall into the path of the lever 19. Upon the next working stroke of lever 19 the loom will be stopped even though one or the other of the branch circuits is closed.

If a warp fault should occur when the shuttle fails to close switch SS electro-magnet 61 will not be energized, but the loom will stop due to opening of both branches of the protector circuit. If this stopping should occur while switch TS is still open, and the weaver, after placing the shuttle in the shuttle box, restarts the loom, electro-magnet 61 will be energized as soon as the loom has turned far enough to close switch TS and the loom will be stopped a second time, whereupon the warp fault can be corrected. When the warp stop circuit is closed and switch 63 opens as a result of loom stoppage, electro-magnet 61 will become deenergized, but a signal circuit including wire 60, lamp L, and wire 61 will be completed through bar 26 and one of the branch circuits.

From the foregoing it will be seen that the invention sets forth simple means for utilizing a single solenoid and a single knock-off mechanism for a loom having an electric warp stop motion and electric protection. The protection circuit which maintains the solenoid energized is under control of a switch which is opened when the warp stop circuit is closed, thereby permitting link 18 to fall into the path of lever 19 even though the shuttle is running properly. Link 18 can also be released to fall to stopping position by deenergization of the solenoid 16 by failure of the shuttle to arrive at a given point along the lay at the correct time in the loom cycle. In either type of stoppage the link 18 will fall into the path of a lever 19 and the latter will be timed so as to bring the loom to rest while the lay is still a sufficient distance behind front center so that should the shuttle be trapped in the warp shed there will be no warp smash.

Having thus described the invention it will be seen that changes and modifications of the foregoing specific disclosure may be made without departing from the spirit and scope of the invention.

What is claimed as new is:

1. In stopping means for a loom operating with a shuttle, loom protection electric circuit means normally closed when the shuttle is running properly, a normally energized electro-magnetic device in said protection circuit means, loom stopping mechanism controlled by the device

effective to stop the loom when the device is deenergized, normally open warp stop electric circuit means closed upon occurrence of a warp fault, and normally closed switch means in said protection circuit means controlled by the warp stop circuit means and opened when the latter circuit means is closed to open the protection circuit means to effect deenergization of said device and thereby enable the stopping mechanism to stop the loom.

2. In stopping means for a loom operating with a shuttle, stopping mechanism capable of effecting loom stoppage at a given time in the loom cycle, an electro-magnetic device effective if energized at said given time to prevent the stopping mechanism from stopping the loom, said stopping mechanism being effective to stop the loom if the device is deenergized at said given time, loom protection electric circuit means controlled by the shuttle causing said device to be energized at said given time if the shuttle is running properly, normally open warp stop electric circuit means closed upon occurrence of a warp fault, and means operative upon closure of the warp stop circuit means to prevent energization of the device by the protection circuit means and thereby enable the stopping mechanism to stop the loom.

3. In stopping means for a loom operating with a shuttle, stopping mechanism capable of effecting loom stoppage, an electro-magnetic device effective if energized at a given time in the loom cycle to prevent the stopping mechanism from stopping the loom, said stopping mechanism being effective to stop the loom if the device is deenergized at said given time, loom protection electric circuit means controlled by the shuttle causing said device to be energized at said given time if the shuttle is running properly, normally open warp stop electric circuit means closed upon occurrence of a warp fault, and means operative upon closure of the warp stop circuit means to prevent the protection circuit means from energizing the device and thereby enable the stopping mechanism to stop the loom.

4. In stopping means for a loom operating with a shuttle, stopping mechanism operating to stop the loom at a given time in the loom cycle, an electro-magnetic device controlling the stopping mechanism effective when energized to prevent the mechanism from stopping the loom, said mechanism being effective to stop the loom when the device is deenergized, loom protection electric circuit means including said device and two branches in parallel one or the other of which will be closed to maintain the device energized so long as the shuttle is running properly, normally open warp stop electric circuit means, a normally closed electric switch in said protection circuit means through which electric current normally flows to one or the other of said branches; and electro-magnetic means effective upon closure of the warp stop circuit means to open said switch and thereby deenergize the device.

5. In stopping means for a loom operating with a shuttle, stopping mechanism capable of stopping the loom at a given time in the loom cycle, an electro-magnetic device controlling said stopping mechanism, loom protection electric circuit means including a normally closed switch in series with said device and including also two branch circuits one or the other of which will be closed if the shuttle is running properly to maintain said device energized, and normally open warp stop electric circuit means including

electromagnetic means to open said switch and thereby open the loom protection circuit means to deenergize said device upon closure of said warp stop circuit means, provided one or the other of said branch circuits is closed, said stopping mechanism being effective to stop the loom upon deenergization of the device.

6. In stopping means for a loom operating with a shuttle, stopping mechanism capable of stopping the loom at a given time in the loom cycle, an electro-magnetic device controlling said stopping mechanism preventing the latter from stopping the loom if the device is energized at said time, loom protection electric circuit means including a normally closed switch, said device and two branch circuits in parallel, one of said branch circuits opening periodically and the other branch circuit being closed by the shuttle at said given time if the shuttle is running on time, said device being deenergized if both branch circuits are opened simultaneously, and normally open warp stop electric circuit means including an electromagnet controlling said switch, closure of said warp stop circuit means due to warp failure energizing said electro-magnet with a consequent opening of said switch and said loom protection circuit means to effect deenergization of the device, said warp stop circuit means being completed through one or the other of said branch circuits.

7. In stopping means for a loom operating with a shuttle, stopping mechanism including an actuator having a working stroke at a given time in the loom cycle and including also a force transmitting element tending normally to move into the path of the actuator and effective to stop the loom when the actuator has said working stroke provided the element is in said path, loom protection electric circuit means including a normally closed switch and an electro-magnetic device controlling said element and effective if closed at said given time to energize said device and cause the latter to hold the element out of said path, said protection circuit means being closed at said given time to energize the device provided the shuttle is running on time, and normally open warp stop electric circuit means including an electro-magnet normally deenergized but effective when energized upon closure of said warp stop circuit means to open said switch in the loom protection circuit means to cause deenergization of the device with resultant movement of said element into said path.

8. In stopping means for a loom operating with a shuttle, stopping mechanism capable of effecting loom stoppage, an electro-magnetic device effective if energized at a given time in the loom cycle to prevent the stopping mechanism from stopping the loom, said stopping mechanism being effective to stop the loom if the device is deenergized at said given time, a single source of electric power, loom protection electric circuit means including said source controlled by the shuttle causing said device to be energized at said given time if the shuttle is running properly, normally open warp stop electric circuit means including said source closed upon occurrence of a warp fault, and means operative upon closure of the warp stop circuit means to prevent the protection circuit means from energizing said device.

9. In stopping means for a loom operating with a shuttle, stopping mechanism capable of stopping the loom at a given time in the loom cycle, an electro-magnetic device effective if energized

at said given time to prevent stopping of the loom by said mechanism, the latter being effective to stop the loom if said device is deenergized at said given time, a single source of electric power, loom protection electric circuit means controlled by the shuttle causing said device to be energized at said given time if the shuttle is running properly, normally open warp stop electric circuit means including said source closed upon occurrence of a warp fault, and means 10 operative upon closure of the warp stop circuit means to prevent energization of said device by said protection circuit means and thereby enable the stopping mechanism to stop the loom.
